AUTOMATIC RELEASE MECHANISM FOR LOCKS

Filed March 29, 1922

2 Sheets-Sheet 2

UNITED STATES PATENT OFFICE.

ALFRED J. MACY, OF CHICAGO, ILLINOIS, ASSIGNOR, BY MESNE ASSIGNMENTS, TO THE PRO-TEX CORPORATION, OF CHICAGO, ILLINOIS, A CORPORATION OF ILLINOIS.

AUTOMATIC RELEASE MECHANISM FOR LOCKS.

Application filed March 29, 1922. Serial No. 547,616.

This invention relates to means for automatically operating a supplemental door lock when an attempt is made to unlawfully force or tamper with the regular fastening means.

A further object of this invention is to provide such a releasing mechanism which is adapted to be fitted over existing door locks in such a way that attempted removal 10 of said lock will cause the operation of this device to bring a supplemental lock into operation.

A further object is to so arrange the mechanism that other vulnerable parts of the 15 door can be protected thereby so that an attack on such vulnerable parts will cause the mechanism to operate.

A further object of the invention is to sound a warning means when the mechanism 20 is released to frighten away persons attempting unlawful entry before they can solve the operation of the auxiliary lock used in connection with this device.

Other and further important objects of 25 this invention will be apparent from the disclosures in the specification and the accompanying drawings.

The invention (in a preferred form) is illustrated in the drawings and hereinafter 30 more fully described.

On the drawings:

Figure 1 shows a rear elevation of a vault door with the device of this invention installed thereon.

Figure 2 is an enlarged fragmentary elevation of the device shown in Figure 1.

Figure 3 is a slightly enlarged side elevation of the device shown in Figure 2.

Figure 4 is a slightly enlarged section on the line 4-4 of Figure 2 showing the device in place on a vault lock.

Figure 5 is a slightly enlarged section on the line 5-5 of Figure 2.

Figure 6 is an enlarged section on the line 45 6-6 of Figure 5.

Figure 7 shows a fragmentary rear elevation of a vault door with a modified form of the device of this invention installed thereon.

Figure 8 is an enlarged fragmentary elevation of the device shown in Figure 7.

Figure 9 is a side elevation of the device in partial section along the line 9-9 of Figure 8.

Figure 10 is an enlarged section on the line 10-10 of Figure 8. 55

Figure 11 is an enlarged section on the line 11-11 of Figure 10.

As shown on the drawings:

A description of the device as installed on an ordinary vault door follows, it being 60 understood that the invention is not limited to such a class of closures, but may be constructed in a large variety of ways suitable to other kinds of doors; and with other forms of auxiliary locks besides the one illustrated here and described in my copending application for an "automatic safety lock for vault and safe doors," which has issued as Patent No. 1,551,580. 65

In the diagrammatic view of the rear 70 of a vault door shown in Figure 1, the numeral 1 refers to the steel plate used as the front and principal part of such a door, with sliding locking bolts 2 arranged on the back thereof and tied together by a plurality of bars 3 against one of which the usual combination or time lock 4 operates to hold the bolts 2 extended when in locking position. An auxiliary lock 5 is also shown on Figure 1. The particular lock illustrated 75 projects a threaded shaft against one of the bars 3 when the weight 6 is released by the trigger 7. 80

A device embodying the present invention is shown in detail in Figures 2 to 6 inclusive. 85 The back plate 8 is so formed with slots as to fit over the usual form of combination lock 4, to be held thereto by the screws 9 which are used to hold the cover of said lock 4 in place. The back plate 8 has a plurality of bosses 10, 11 and 12 formed from the material of the plate, those marked 10 being used to hingedly support a front plate 13 at one end, the other end of said front plate 13 being normally held away 90 from the back plate 8 by an adjustable screw 14 abutting against some part of the door itself outside of the combination lock. A screw 15 and a spring 16 fastened to the back plate and engaging the front plate serve to force the latter against the former, against the holding action of the screw 14. 95

The bosses 11 and 12 are for holding a tube 17 through which a soft metal wire 18 is threaded. One end of this wire is fastened to the outboard end of the tube, the 100 105

other end being fastened to one end of a bell crank 19 mounted on a stud 20 on the back plate. The bell crank is connected to the auxiliary lock in any convenient manner, in 5 this case by a cord 21 to the trigger 7. The underside of the front plate is provided with a knife blade 22 which acts in connection with the boss 12 as a shear to cut the wire 18 thereby releasing the weight 6 by 10 means of the bell crank, cord and trigger. It will be obvious that as long as the screw 14 remains in place as adjusted upon installation, the shearing members are inoperative, so that the wire 18 holds the auxiliary lock open.

An insulated block 23 has electrical contact points 24 adapted to be closed by one arm of the bell crank if the wire should be cut. These contacts are wired through a 20 battery 25 and a buzzer or other sound producing means 26 mounted in any convenient place, preferably on the inside of the door.

The operation is as follows:

Under ordinary operating conditions this 25 device remains unaffected and inoperative. Should an attempt be made to force the combination lock or remove same, the contact of the screw 14 with the surface of the door will be altered, allowing the spring 16 to 30 force the front plate in, cutting the wire 18 in the shearing arrangement 12, 22, thereby causing the operation of an auxiliary lock. At the same time the movement of the bell crank also makes a closed circuit for the 35 buzzer or similar device 26, which is intended to disturb a burglar and discourage a continuation of his attempt at entry.

It is to be noted that the inertia of the member 13 would be sufficient when subjected 40 to a shock to cut the wire even in case of failure of the spring 16 to sever the wire.

The long tube 17 and wire 18 are intended 45 to be arranged around other vulnerable parts of the door locking mechanism in such a way that an attempt to get at such parts would result in cutting the tube and wire, producing the same result as an operation of the shearing elements in the device itself.

The screw 35 takes no part in the operation 50 of the lock and is only used temporarily to permit complete assembly of the device at the factory, it being removed when said device is installed on a door.

An alternative arrangement suitable for 55 use with a spring operated bolt could be made by arranging to have the wire 18 extend directly to an ordinary spring bolt so that cutting the wire allows said spring bolt to slide into a recess in the door frame.

A modification of this device is shown in 60 Figures 7 to 11 inclusive. Parts identical in form and function in both embodiments of the invention bear the same numerals. The operation of the wire, bell crank, etc., is the same in both forms, the difference being in

the method of attachment and the means for cutting the wire.

The plate 27 is mounted over the usual permutation or time lock by the screws 28, 29, 30. The screw 30 is fastened to a moving block 31 which is carried by a recessed block 32 which is fastened to the door by a screw 33. The block 31 has a large hole for the tubing and a small hole for the wire which registers with a similar hole in the block 32 when the block 31 is seated in the recess. The arrangement of the screws 28 to 30 is such that the block 31 will normally be held seated in the recess. With the wire 18 threaded through these holes to hold the lock open, it will require a very heavy jar or an attempt to force the lock to cause the plate 27, screw 30 and block 31 to move outward thereby cutting the wire and releasing the auxiliary lock operating mechanism. In both forms of my device cutting or burning the tube and wire at any place will release the wire and allow it to be pulled through the remaining part of the tube thereby operating the emergency lock. 90

In this case the bell crank 19 is mounted on an arm 34 clamped by the block 32, as shown in Figure 11. It is of course possible to adapt the signaling device to the bell crank in this modified form.

95 I am aware that numerous details of construction may be varied through a wide

range without departing from the principles

of this invention, and I therefore do not pur-

pose limiting the patent granted otherwise

than necessitated by the prior art.

100 I claim as my invention:

1. The combination with vault doors, including the locks therefor, of an additional emergency lock, and operating mechanism therefor, consisting of a supporting plate adapted to fasten over the regular lock, means adapted to hold said emergency lock in an inoperative position, and means connected with said supporting plate for cutting said first mentioned means and thereby locking said auxiliary lock when said regular lock is forcibly tampered with.

110 2. In a device of the class described, a door, a lock for the door, an emergency lock, means for operating said emergency lock when the regular lock is abused, consisting of means adapted to hold said emergency lock inoperative, said means being fastened at one end in a tube which can be led to 115 any vulnerable point in the lock operating mechanism of the door, and means for cutting said wire whereby the emergency lock will be operated to prevent unlawful entry.

120 3. The combination with an auxiliary locking means, of means for controlling said lock, consisting of a semi-flexible tube, a wire threaded through said tube and fastened to one end of the tube, a bracket for holding the other end of said tube, means on 125

130

said bracket for cutting said wire when the bracket is jarred or moved, and connecting means between said wire and the auxiliary lock to hold said lock inoperative until said

5 wire shall be cut.

4. A device of the class described comprising a locking mechanism, a semi-flexible tube, lock restraining means in said tube and means for severing the restraining means to

10 permit operation of said locking mechanism.

5. The combination of a closure, of a safety locking device therefor, and a tensioned wire within a tube normally restraining said locking device, said wire and tube
15 being adapted to be disposed over the vulnerable parts of the closure in positions adapted to sever the tube and wire upon an attempt at forceful entry.

6. The combination with a closure and
20 locking means therefor, of a supplemental

locking means, and operating means therefor, comprising a Bowden wire extending to the vulnerable parts of the first mentioned locking means for said closure, and means whereby a forceful attempt to unlawfully
25 release said vulnerable parts will result in severing said Bowden wire, thereby operating said supplemental locking means.

7. In combination with a lock, a lock restraining mechanism adapted to normally
30 hold the lock inoperative, comprising a severable tension member attached at one end to the lock mechanism, and a non-compressible member attached to the free end of the tension member adapted to serve as a strut
35 to normally maintain the tension in said member.

In testimony whereof I have hereunto subscribed my name.

ALFRED J. MACY.
